UNITED STATES PATENT OFFICE.

ZENO C. BREWSTER, OF OXFORD, NEW YORK.

PRESSURE-REGULATED AIR-VALVE.

No. 833,368.

Specification of Letters Patent.

Patented Oct. 16, 1906.

Application filed June 20, 1905. Serial No. 266,184.

To all whom it may concern:

Be it known that I, ZENO C. BREWSTER, a citizen of the United States, and a resident of Oxford, in the county of Chenango and State 5 of New York, have invented certain new and useful Improvements in Pressure-Regulated Air-Valves for Air-Compressors, of which the following is a specification.

My invention relates to a valve for opening 10 and closing the intake-pipe of air-compressing apparatus, which valve is in turn controlled by the pressure in the receiver, service-pipe, or other container of the air being compressed.

15 It is quite usual to employ the pressure of municipal or other water system to actuate hydraulic air-compressors for developing air-pressure for various purposes, and for many uses to which such air-pressure is applied it 20 is very desirable to maintain a constant pressure and to employ means which will stop and start the action of the hydraulic air-compressor automatically as the pressure of air in a storage-receptacle reaches or falls below the predetermined degree. Automatic 25 devices for this purpose have usually been in the nature of valves controlled by a pressure-diaphragm and made to open and close the water-supply of the hydraulic air-compressor; but it has never been practicable to 30 maintain the air compression constant with an automatic valve applied to the water-supply, owing to the comparatively large and variable service-pressure to be controlled.

35 The objects of my present invention are to provide a system of control and a novel construction of automatic valve employed therein, whereby a predetermined degree of compression developed in a storage-receptacle by 40 a hydraulic compressor may not only be maintained with great accuracy, but very slight changes in such pressure will be effective to actuate the automatic valve regardless of changes in the service water-pressure.

45 In carrying out my invention I operate wholly upon the air-intake of the hydraulic compressor in controlling the action of the same, my system of control depending upon the fact that if the air-intake is closed the 50 water cannot gravitate from the otherwise tight compression-chamber, and the pump or compressor ceases with the last pulsation that brings the pressure to the predetermined degree. Inasmuch as I am dealing 55 with air at normal atmospheric pressure in arresting the compressing operation instead

of with the varying pressure of the water in the service-pipe, it follows that I can operate the automatic valve with substantial balance between the pressure on the diaphragm that 60 closes the valve and the spring that opens it, so that the slightest overbalance in either direction by reduced or increased reservoir-pressure is followed by immediate response of the valve to start or arrest the compressor, and consequently the predetermined 65 degree of compression will be maintained with great accuracy, nor will this result be affected in any way by other influences, since the unchanging normal atmospheric pressure 70 alone can affect the valve. To further reduce the work of cutting off the air-intake, its inlet end is reduced to a comparatively thin edge, against which a flat valve-packing (preferably of rubber to enable it to contact 75 all around) is seated by the diaphragm when the pressure is full and from which the valve-packing is unseated by spring-pressure when the pressure falls.

My invention will be fully understood upon 80 reference to the accompanying drawings, in which—

Figure 1 is a general view of a hydraulic air compressing and storing apparatus to which my present invention is applied. Fig. 85 2 is a longitudinal axial section of the pressure-controlled air-valve, and Fig. 3 is a detail view.

1 represents a container or receptacle for receiving and holding air under pressure. 90

2 represents a hydraulic air-compressor of known construction which contains a controlling-float 3, water-discharge pipe 4, water-inlet 5, air-intake 6 with a check-valve 7, and air-discharge pipe 8 with a check-valve 95 9. As water runs out of the pump 2 and creates a vacuum air enters through pipe 6 under external atmospheric pressure. When float 3 settles to a predetermined point, the water-discharge 4 is closed, inlet-pipe 5 is 100 opened, and the pump again fills with water, holding check-valve 7 closed and forcing the contained air out through pipe 8 into reservoir 1. When the air is practically discharged and float 3 has reached its upper 105 limit, supply-pipe 5 is closed and discharge-pipe 4 is opened, the water again discharges by gravity, and a new charge of air enters through pipe 6, check-valve 9 remaining closed under back pressure from the reservoir. The float, having thus again descended, 110 again shifts the water-valves, and the

previously-described pumping action is repeated.

My present invention operates upon the principle that if the air-intake 6 is closed the water will not gravitate out of the tight chamber of pump 2, and consequently the pumping action will cease under the last impulse of the incoming water after the pressure in the reservoir reaches a certain degree.

10 One feature of my invention therefore consists in applying to the intake of an air forcing and pumping apparatus a cut-off valve operated automatically by the pressure of the air being supplied for consumption, so as 15 to open the intake when the pressure falls below a given degree and close said intake when the pressure reaches the desired point.

In order to accomplish the above-named object, I have provided a novel construction 20 of automatic valve 10, supported in proper relation to the inlet end of the intake 6 and connected by a pipe 11 with the supply-pipe or a reservoir or other container which is being supplied with air or connected with a 25 service-pipe into which the air is being forced.

The construction of the automatic valve 10 will be best understood upon reference to Figs. 2 and 3, wherein pipe 6 has supported in suitable relation to its open end an expandable diaphragm 12, secured over an expansion-chamber 13, which has a connection, such as pipe 11, through which it is subjected to control of the air-pressure to be regulated. Diaphragm 12 is suitably loaded by a known 35 means to hold it away from the end of pipe 6 whenever pressure in the chamber 13 falls below a predetermined degree, either equal or proportional to the pressure it is desired to maintain in the reservoir—that is to say, it 40 is equal to such pressure if pipe 11 communicates directly with the reservoir, but is proportional to the pressure in the reservoir if a reduction-valve or other means is introduced in said pipe. In cases where very high pressures are being stored a reduction-valve can 45 be used to advantage.

The means employed for loading the diaphragm 12 is preferably a rigid disk 14, resting above said diaphragm and forming the 50 abutment for one end of each of a pair of springs 15, which abut at their opposite ends against a follower 16. Follower 16, as well as the springs 15, are guided by rods 17, projecting rigidly from the walls of chamber 13 55 and secured at their upper ends to a yoke 18, which affords convenient means for supporting the entire valve on the pipe 6. The diaphragm 12 is adjustable relatively to the pipe 6 for varying the opening at the end of 60 said pipe by having yoke 18 threaded on the pipe 6 and held to its adjustment by jam-nut 19. This adjustment provides for proximately determining the degree of pressure required beneath the diaphragm to close the 65 intake-pipe. For the purpose of predeter-

mining this pressure with accuracy I vary the load imposed by springs 15 upon the disk 14, and consequently upon the diaphragm 12, by providing a milled hand-nut 20, threaded on the pipe 6 above the follower 16 and 70 adapted to depress the follower and compress the springs 15 to any desired degree. I so balance the valve between the diaphragm-pressure on one side and spring-pressure on the other as to cause it to close the intake immediately upon obtaining the desired pressure in the reservoir and to cause it to open the intake under the slightest reduction from said pressure, so that the pump may 75 again compress the air to the number of 80 pounds required. The fact that I am dealing with so light a medium as the atmosphere at normal pressure in controlling the pump enables me to work with a substantial balance between loads on opposite sides of the 85 valve and obtain such delicacy of operation. Under these conditions I can with slight adjustments of the hand-nut change the degree of pressure that will be maintained at will. In order to reduce wear upon the diaphragm 90 12, and thus avoid puncturing it and putting the device out of action, as well as wasting pressure in the reservoir in the event of such mishap, a packing 21 is interposed between the diaphragm and the disk 14. This packing 95 is preferably of flexible material, such as rubber or the like, in order that it may seat evenly against the end of pipe 6, which is reduced to a thin edge to facilitate seating and to reduce the work required to make a tight 100 closure. As shown in Fig. 3, the packing 21 fits upon the guide-rods 17 by peripheral notches. It thus becomes very convenient to raise the disk 14 and remove a badly-worn packing 21 and to quickly replace it by a 105 new packing without appreciably interrupting the automatic control of the pump.

While I have disclosed more or less in detail the specific construction of valve that I have found to be effective for the purpose 110 stated, I desire it to be understood that I do not limit myself to the particular details herein disclosed, as it is obvious that many changes might be made without departing from the scope of my invention. I also desire it to be understood that my invention is not limited in its application to the particular type of hydraulic air-compressor herein selected for purposes of illustration. The device is obviously applicable to any type of 120 air-forcing mechanism where an interruption of the air-intake will cause temporary cessation of the operation.

Having thus described my invention, what I claim, and desire to secure by Letters Patent, is—

1. In an air-compressor, the combination of an air-intake pipe having one end open toward the atmosphere, a valve adapted to move toward and from the open end of the 130

intake-pipe and having one side subject to the pressure of the atmosphere, springs acting on the valve in conjunction with the atmospheric pressure, and a connection whereby the other side of the valve is subject to the pressure of the compressed air.

2. In an automatic valve, the combination of the air-intake pipe, the pressure chamber and diaphragm, the rods projecting from the pressure-chamber, the springs surrounding the rods for holding the diaphragm away from the pipe, and the packing interposed between the diaphragm and pipe and releasably engaging the rods by peripheral notches.
- 15 3. In an automatic valve, the combination of the air-intake pipe, the yoke screwed there-

on the follower and its adjusting-nut working on said pipe, the side rods projecting from the yoke and guiding the follower, the disk guided by said rods, the springs surrounding the rods and interposed between the follower and disk, the pressure-chamber supported by the rods, the diaphragm over said chamber, and the packing interposed between the diaphragm and intake-pipe.

The foregoing specification signed at Washington, District of Columbia, this 7th day of June, 1905.

ZENO C. BREWSTER.

In presence of—

HERVEY S. KNIGHT,
EDWIN S. CLARKSON.
